UNITED STATES PATENT OFFICE.

ALEXANDER WINTON, OF LAKEWOOD, OHIO.

INTERNAL-COMBUSTION MOTOR AND FUEL-FEED THEREFOR.

1,401,746.

Specification of Letters Patent. Patented Dec. 27, 1921.

Application filed October 16, 1916. Serial No. 125,978.

To all whom it may concern:

Be it known that I, ALEXANDER WINTON, citizen of the United States, residing at Lakewood, in the county of Cuyahoga and 5 State of Ohio, have invented certain new and useful Improvements in Internal-Combustion Motors and Fuel-Feed Therefor, of which the following is a specification.

This invention relates to internal combustion motors and particularly to fuel feeding mechanism such as is shown in my copending application, Serial No. 5995, filed Feb. 4, 1915, for internal combustion motors.

The present invention is for an improved 15 type of cut-off utilized in the fuel supply and preferably actuated by the fuel pump and regulated by the governor for cutting off the supply of fuel on the intake stroke of the fuel pump and limiting such supply 20 at that time to the desired charge. In the embodiment shown the cut-off is in the nature of a slide valve which is circular and is provided with a supply port adapted to register with the supply port leading to the 25 pump, the time of movement of the supply port in the slide valve across the port leading to the fuel pump determining the volume of fuel passing to the pump on its intake stroke thus determining the amount of the charge.

30 The invention may be further briefly summarized as consisting in the construction and combination of parts hereinafter set forth in the following drawings, description and claims.

35 Referring to the drawings Figure 1 is a side elevation of a portion of a multiple cylinder internal combustion motor provided with my device; Fig. 2 is an enlarged view of the fuel pump feeding mechanism 40 showing the several fuel injecting devices; Fig. 3 is a sectional view showing the arrangement of the pump and its slide valve or cut-off; and Fig. 4 is an enlarged detailed view showing the arrangement of the cut-off 45 valve structure.

In the embodiment shown 1 represents the 50 crank case of an internal combustion motor provided with a cylinder 2 having pistons not shown of any preferred construction. The engine is provided with a suitable governor 3 having a grooved collar 4 adapted to actuate a governor lever 5 pivoted at 6 to the frame work of the engine. The governor lever 5 is connected to a downwardly extending rod 7 which in turn is connected to the

controlling device of the fuel injection mechanism as will appear.

The fuel injection mechanism comprises a housing 8 having a fuel supply manifold 9 provided with a plurality of supply ports 10 60 corresponding in number to the number of cylinders. These supply ports 10 register and communicate with other supply ports 11 leading to the several cut-off openings 12 arranged in a main pump and cut-off frame 65 13. All of these cut-off openings 12 communicate with a common source of fuel supply 14. The main pump and cut-off frame is provided with a plurality of pump barrels 15, one for each cylinder, and these receive 70 the several fuel injecting plungers 16 each of which is provided with a suitable stuffing box structure 17 and a cross head portion 18 having a bearing in a cross head guide 19. Each cross head is provided with a pair of 75 upwardly extending ears 20 spaced apart and both to engage within ears 21 of a fork forming a part of an eccentric strap 22 engaging an eccentric 23 upon an eccentric shaft 24. Passing through these ears 20 and 21 is a pivot pin 21'. Each of the pump barrels 15 is provided with a laterally extending port 25 leading out through a portion 26 of the frame 13. Between this portion 26 and the manifold portion 9 are a plurality 80 of valve members 27 provided with suitable recesses forming seats for a plurality of inlet valves 28. Above the portion 26 are a plurality of valve members 29 having 85 openings for receiving discharge valves 30. The uppermost valve member is connected to the discharge pipe 31 leading to the corresponding engine cylinder.

The shaft 24 is mounted in suitable bearings 32 in the housing and is driven by a 90 suitable gear 33 meshing with the gear 34 of any suitable driven shaft of the engine, preferably the cam shaft 35. From the foregoing it will be seen that when the shaft 24 is rotated the several fuel injecting pump 100 plungers will be reciprocated at the proper time due to the fact that the eccentrics 23 are properly timed and located upon the shaft and but for the cut off mechanism to be described the several pumps would receive full 105 charges of fuel from the supply and inject the same to the several cylinders at the proper step in the cycle of operations of the engine.

The cut off mechanism comprises a plu- 110

rality of individual cut off devices actuated and operated by the corresponding fuel injecting pumps and they are all regulated by a common regulating mechanism under 5 the control of the governor and this mechanism will now be described.

Slidably mounted in each of the cut off openings 12 is a cut off valve rod 34 passing through a suitable stuffing box structure 35 10 and pivotally connected at its upper end to a short link 36 in turn pivotally connected to a pin 37 arranged intermediate the ends of an actuating lever 38. One end of this lever is provided with a suitable head 39 pivotally 15 mounted upon the pin 21' in the ears 20 and 21. The opposite end of this lever 38 is provided with a fork portion 40 adapted to engage a crank rod 41 extending throughout the extent of the several injecting 20 devices and at its ends connected to cranks 42 secured to or formed integral with an operating shaft 43.

The lower end of the cut off valve rod is bored to form a chamber 44 which extends 25 for a short distance into the rod and communicates with a lateral port or cut-off opening 45 adapted to register with the opening 11 and permit the passage of fuel to the injecting pump at the proper time.

30 In order to prevent leakage about the rod 34 and to insure a perfect closure of the port 11 against leakage of fuel into this port, suitable mechanism is provided for forcing this rod against the wall of the opening 35 12 about the port 11. This mechanism comprises a follower 46 slidably mounted in a suitable guide opening 47 and having a chamber 48 extending inwardly from one end for receiving a coiled spring 49 which 40 thrusts against a suitable plug 50 threaded into the wall of the opening 47.

The foregoing description so far as the cut off mechanism is concerned has been confined to one separate device but it is obvious 45 that there is one distinct and independent cut off rod and lever for each injecting pump. Secured to the shaft 43 outside of the housing is a controller actuating lever 51 pivotally connected to the downwardly extending rod 7 in turn connected 50 to the governor lever 5.

Fuel is supplied to the opening 14 through a supply pipe 52.

In operation, for example, it is assumed 55 that fuel preferably under pressure is supplied to the supply pipe 52 and that the engine is operating at half speed with the governor set to regulate the cut-off mechanism at this point and the description of the 60 operation will be confined to one complete injecting device which will suffice for all.

As the plunger 16 moves upward on its receiving stroke the lever 38 is moved in a clockwise direction about the crank rod 41 65 as a fulcrum. This causes the cut off valve

rod 39 to move in a manner such that its port 45 permits the flow of fuel to the corresponding injecting pump barrel until this barrel and its plunger have measured a half stroke or charge of fuel when the port 45 70 will have passed the opening or port 11 and further supply of fuel to the pump barrel will be stopped, the plunger finishing its stroke and drawing a partial vacuum for that portion of the stroke. Any leakage 75 from the supply to the opening or port 11 is prevented by the follower 46 which forces the cut off rod against the wall of the cut-off opening 12 about the opening or port 11. If the speed of the engine should drop or 80 increase over that at which the governor is adjusted then the position of the crank rod 41, or in other words the fulcrum of the several levers 38, will be moved in proper manner to adjust the time of the cut off of 85 the several cut off devices to account for the variation in speed and will bring the engine back to its proper speed. It is obvious that the crank rod may be actuated by the governor as shown or by any other 90 mechanism such as a hand controlled device.

Having described my invention, I claim:—

1. In an internal combustion motor, a cylinder, a piston therein, a fuel injecting device for said cylinder having a capacity for a 95 maximum charge and having a constant stroke, means in open communication with said fuel injecting device for supplying fuel in unmeasured quantity thereto, means actuated by said fuel injecting device for interrupting the fuel supply to said device on the suction stroke thereof for determining the volume of the charge, and a check valve mechanism in said supply.

2. In an internal combustion motor, a cylinder, a piston therein, a fuel injecting device for said cylinder having a capacity for a maximum charge and having a constant stroke, means in open communication with said fuel injecting device for supplying fuel 105 in unmeasured quantity to said fuel injecting device, means actuated by said fuel injecting device for interrupting the fuel supply to said device on the suction stroke thereof for determining the volume of the charge, 110 means for controlling the operation of said interrupting means and a check valve in said supply.

3. In an internal combustion motor, a plurality of cylinders, pistons therein, fuel injecting mechanism comprising a fuel injecting device for each cylinder and each having a capacity for injecting a maximum charge and having a constant stroke, means in open communication with said fuel injecting device for supplying fuel in unmeasured quantity to said fuel injecting devices, independent means individual to each fuel injecting device for interrupting the fuel supply to each fuel injecting device on the suc- 125 130

tion stroke thereof for determining the volume of the charge, mechanism for controlling the operation thereof, and a check valve in the supply to each injecting device.

5 4. In an internal combustion motor, a plurality of cylinders, pistons therein, a fuel injecting device for each cylinder and each having a capacity for injecting a maximum charge, means in open communication with the fuel injecting device for supplying fuel in unmeasured quantity to said fuel injecting devices, means individual to each fuel injecting device for interrupting the fuel supply thereto on the suction stroke thereof to determine the volume of the charge, a check valve in the supply to each fuel injecting device, and mechanism, including a governor and common to all said interrupting means for controlling the operation of said 20 interrupting means.

5. In an internal combustion motor, a plurality of cylinders, pistons therein, a fuel injecting device for each cylinder and each having a capacity for injecting a maximum charge, means in open communication with said fuel injecting device for supplying fuel in unmeasured quantity to said fuel injecting devices, individual cut-off mechanism for each fuel injecting device arranged in the supply and comprising a cut off to positively cut off the supply of fuel, a check valve in the supply to each fuel injecting device, and mechanism for operating said cut off and actuated during the suction stroke thereof and by the corresponding fuel injecting means for interrupting the fuel supply for determining the volume of the charge.

6. In an internal combustion motor, a plurality of cylinders, pistons therein, a fuel injecting device for each cylinder and each having a capacity for injecting a maximum charge, means in open communication with each fuel injecting device for supplying fuel in unmeasured quantity thereto, cut off mechanism comprising a cut off valve in the inlet of each injecting device, a check valve in the supply to each fuel injecting device, actuating levers therefor each connected at one point to its cut off valve and at another to an operating part, a fulcrum for each lever, and means for varying the fulcrum point of said levers and thereby varying the time of cut off of said cut off valves.

7. In an internal combustion motor, a plurality of cylinders, pistons therein, a fuel injecting device for each cylinder and each having a capacity for a maximum charge and each having an intake stroke, means for supplying fuel to all of said injecting devices in unmeasured quantity, operating mechanism for said devices, and cut off mechanism individual to the several devices, and each comprising a casing connected to

the supply and to the corresponding fuel injecting device, a cut-off member for interrupting the passage of fuel to the corresponding fuel injecting device, an operating lever connected to said cut off member and actuated by the means for operating the corresponding fuel injecting device, and means for controlling the operation of said lever.

8. In an internal combustion motor, a plurality of cylinders, pistons therein, fuel injecting devices each having a capacity for a maximum charge and each having an intake stroke, means for supplying fuel to all of said injecting devices in unmeasured quantity, operating mechanism for said devices and cut off mechanism individual to each device and each comprising a casing connected to the supply and to the corresponding fuel injecting device, a cut off rod for interrupting the passage of fuel to the corresponding fuel injecting device, an operating lever connected to said cut off rod and actuated by the means for operating the corresponding fuel injecting device, there being a lever for each fuel injecting device, a controlling device engaging one end of each of said levers and changing its fulcrum point thereby varying the time of cut off, and means for governing the operating of said controlling device.

9. In an internal combustion motor, a cylinder, a piston therein, a fuel injecting device for said cylinder having a capacity for a maximum charge and having a constant stroke, means in open communication with said fuel injecting device for supplying fuel in unmeasured quantity thereto, means actuated by said fuel injecting device for interrupting the fuel supply to said device on the suction stroke thereof for determining the volume of the charge, and a plurality of check valves arranged in tandem in said supply.

10. In an internal combustion motor, a plurality of cylinders, pistons therein, fuel injecting mechanism comprising a fuel injecting device for each cylinder and each having a capacity for injecting maximum charge and having a constant stroke, means in open communication with each fuel injecting device for supplying fuel in unmeasured quantity thereto, independent means individual to each fuel injecting device for interrupting the fuel supply to said device on the suction stroke thereof for determining the volume of the charge, mechanism for controlling the action thereof, and a plurality of self-closing check valves arranged in tandem in the supply.

In testimony whereof I affix my signature.

ALEXANDER WINTON.
